(57) **CLAIM**

The ornamental design for a combined watch case and portion of a strap, as shown and described.

DESCRIPTION

FIG. 1 is a perspective view of a combined watch case and portion of a strap showing my new design;

FIG. 2 is a front elevation thereof;

FIG. 3 is a rear elevation thereof;

FIG. 4 is a top view thereof;

FIG. 5 is a bottom plan view thereof;

FIG. 6 is a left side view thereof; and,

FIG. 7 is a right side view thereof.

The broken line showings are environmental only and form no part of the claimed design.
